UNITED STATES PATENT OFFICE.

EBEN F. WILDE, OF ATTLEBORO, MASSACHUSETTS, ASSIGNOR TO THE BAER & WILDE COMPANY, OF ATTLEBORO, MASSACHUSETTS, A CORPORATION OF MASSACHUSETTS.

CUFF BUTTON.

Application filed July 14, 1922. Serial No. 575,009.

To all whom it may concern:

Be it known that I, EBEN F. WILDE, a citizen of the United States of America, and resident of Attleboro, in the county of 5 Bristol and State of Massachusetts, have invented new and useful Improvements in Cuff Buttons, of which the following is a specification.

This invention concerns cuff buttons and 10 relates more particularly to cuff buttons of the separable type comprising two members each having a head and a radial flange connected by a suitable shank, the flanged end of one member having a socket or female 15 part for engagement with a stud or male part projecting from the flanged end of the other member.

It is usual for convenience in manufacture to make such buttons of relatively soft material 20 and thus the stud or male part offers little resistance to wear, its holding power rapidly diminishing with use. In the ordinary form of snap button the opposing faces of the flanges are convex so that the combined thickness of the flanges is undesirably great and a substantial crack appears between their edges, while the convex faces of the flanges tend to roll or rock on each other when the button parts are subjected to 25 transverse pressure, causing undue wear of the stud and tending to withdraw the latter from its socket.

Principal objects of the invention are to 30 provide a separable cuff button having a stud member of wear-resistant material such for example as steel, together with simple means for positioning and retaining such stud relatively to the part upon which it is mounted, and also to provide meeting 35 surfaces for the button parts of such a character as to avoid any substantial tendency of the parts to rock relatively to each other.

In the accompanying drawings there is 40 illustrated by way of example, a preferred arrangement of parts whereby the above objects may be obtained.

Fig. 1 is a side elevation of the button forming the subject-matter of the present invention, the separable members thereof being shown as separated;

Fig. 2 is a similar view, but showing such members as united;

Fig. 3 is a composite view showing, in edge elevation and in fragmentary front elevation, respectively, a cap or retaining plate

for securing the stud element in operative position;

Fig. 4 is a side elevation of the stud member;

Fig. 5 is a side elevation of the shank element of the male member of the button;

Fig. 6 is an edge elevation of a head-supporting plate, cooperable with the shank member shown in Fig. 5;

Fig. 7 is a composite view showing, in edge elevation and in fragmentary front elevation, respectively, a head member co-operable with the plate shown in Fig. 6;

Fig. 8 is an edge elevation of a socket plate forming a part of the female member of the button;

Fig. 9 is a front elevation, and Fig. 10 is a side elevation of the shank element of such member;

Fig. 11 is a side elevation of a head supporting plate cooperable with the shank member of Fig. 10;

Fig. 12 is a composite view showing, in edge elevation and in fragmentary front elevation respectively, a head cooperable with the supporting plate of Fig. 11; and

Fig. 13 is a fragmentary diametral section on a line such as I—I of Fig. 2.

Referring to the drawings, the letters A and B respectively indicate generally the male and female members of the separable button, such members having the shank portions 1 and 2, respectively. Referring more particularly to Figs. 3 to 7, and 13, the shank 1 of the male member is shown as provided with a dished flange 3 outstanding from one of its ends. Cooperating with such flange is a cover or retaining plate 5 of annular form, having a central opening 6 and a flanged edge portion 7, such edge portion, when the parts are in operative position, being bent backwardly as indicated at 7^a, Fig. 13, to enclose the peripheral edge of the flange 3, thereby interlocking such flange and plate, and holding the parts in fixed relationship.

Reference character C, Fig. 4, indicates generally a stud element employed in the construction of member A. This stud member is preferably drawn from sheet steel, and comprises a shank portion 10 having a base member at one end, including a radial flange 11, and having a bulbous head 12 at its opposite end. This head is of a diameter such as to permit it to pass through the

opening 6 of cap 5, the flange 11, however, being of larger diameter. The base of the stud is furnished with a shoulder 13, and when the parts are assembled, the edge of 5 the opening 6 in plate 5 engages this shoulder, thus centering the stud relatively to the shank 1, while the flange portion 11 engages the inner surface of the flange 3, as indicated at 14. Preferably the shank 10 member 1 is of tubular construction, the dished flange 3 with the plate 5 forming a cavity or chamber 4. In assembling the stud and the retaining cap or plate 5 with the flange 3, sufficient pressure is exerted in 15 uniting the parts to press the plate 5 inwardly with respect to the cavity 4, so that the outer surface of such plate is concave, as indicated at 15, thus substantially reducing the size of cavity 4 and causing the 20 edge of plate 5 surrounding opening 6 to bear against the shoulder 13. The pressure exerted in uniting the parts is also usually sufficient to dish the outer portion of the flange 11 of the stud so as to cause it to 25 seat firmly against the inner surface of flange 3, the stud thus being securely clamped between the cover plate and the flange 3. The stud 1 is provided with a rib 16 and a sleeve portion 17, the latter being 30 of a diameter to pass through a central opening 18 in the plate 19 and when assembled with such plate being flanged over against the concave face of the latter. A head 20, of any desired ornamental character, and having a flanged edge 21, is secured to the supporting plate 19 by bending the edge 21 inwardly over the edge of 35 such supporting plate.

Referring now to Figs. 8 to 13, the member B of the button comprises the tubular shank 2 having the outstanding and substantially radial flange 22. A cover plate 23 is associated with this flange, such cover plate having a central opening 24 defined 40 by a tubular flange or sleeve 25, and having a peripheral flange 26 which, in assembling the cover plate with the flange 22, is bent backwardly as indicated at 26^a, Fig. 13, so as to overlap the edges of such flange, 45 thereby fixedly uniting the parts. The flange 22 is of dished form, thus providing a relatively deep chamber 28, the outer surface of the plate 23 being of convex curvature as indicated at 29. The convexity of 50 the plate 23 is complementary to the concave curvature of the plate 5 so that such parts closely interfit when assembled, thus preventing any tendency of the members A and B to rock or tip relatively to each other, 55 while at the same time the combined thickness of such parts is reduced and the crack usually appearing at the point of union of such members is substantially eliminated. The cavity 28 provides space for a spring 60 65 30, preferably of U form, and comprising the

oppositely disposed end portions 31 and 32 which project into slots 39 formed in the opposite walls of the sleeve 25. The spring elements 31 and 32, as thus arranged, obstruct the passage through the sleeve 25 to a certain extent and are adapted to engage the stud element C below the head 12 thereof whereby to secure the members A, B in operative position. This spring 30 may be of steel or other suitable material 70 and is of sufficient resiliency to permit the head 12 of the stud to be forced into its socket or to be withdrawn therefrom when desired. The shank member 2 is also provided with a shoulder 33 and a sleeve portion 34, the latter being adapted to pass through an opening 35 in a plate 36 and to be flanged over against the rear surface of such plate, thus holding the assembled parts in proper relationship. Associated 80 with the plate 36 is a head 37, of any desired material and provided with a peripheral flange 38, which, when assembled with the part 36, is bent inwardly over the edges of the latter. 90

The button as thus formed is of very durable construction, as the stud member may be made of hard and wear-resistant material, such for example as steel, while the remainder of the button may be formed of 95 the usual relatively soft alloys commonly employed for such purposes. The arrangement employed for holding the stud in proper position accords with the use of complementary engaging surfaces of concave and convex form for the purpose of preventing relative rocking or rolling of the button parts as the base of the stud as above described is readily secured within the relatively shallow cavity behind the concave plate 5 while the deeper cavity behind the convex plate 23 serves to enclose the spring 30 or its equivalent. Although under some circumstances it might be desirable to arrange the stud to project from the convex surface, it is preferred, to combine the stud with the member having the concave surface for the reasons above pointed out. 100

What I claim and desire to secure by Letters Patent of the United States is.— 115

1. A cuff button having male and female members, the male member thereof comprising a body portion having a head at one end and a stud member fixedly embedded in said body portion at its other end and 120 projecting therefrom, said stud member being of drawn sheet steel.

2. A cuff button having a male member comprising a shank of relatively soft material having a head fixed at one end thereof, a hollow stud of drawn sheet steel arranged coaxially with the shank at the opposite end thereof, and means for fixedly securing said stud in operative relationship 125 to the shank. 130

3. A cuff button having separable members, one of said members comprising a shank having a head at one end thereof terminating at its other end in a substantially radial flange, a stud member provided with a flange of a diameter smaller than that of said first flange and resting against the latter, and means for fixedly securing said flanges in operative relationship. 70
- 10 4. A cuff button having a male member comprising a tubular shank provided at one end with a fixed head and at the other with an outstanding flange, a plate provided with a central opening having its outer edge fixedly secured to the edge portion of said flange, and a wear-resistant stud member having a head portion projecting through the opening in said plate and a base portion of a diameter larger than that of the opening fixedly clamped between the flange and plate. 75
- 15 5. A cuff button comprising separable members of relatively soft material, each having a head at one end and being provided at their other ends with complementary engaging surfaces, one of said surfaces being convex and the other concave, and an independent stud member of wear resistant material fixedly secured to one of said members and projecting axially from one of said surfaces, the other of said surfaces having an axial socket opening for the reception of said stud member and a spring associated with said socket opening for resiliently engaging the stud. 80
- 20 6. A cuff button having separable members each comprising a tubular shank provided at one end with a fixed head and at the other with a hollow flange, a stud of wear-resistant material having a base fixedly secured within the hollow flange of one of said members and having a head projecting axially therefrom, and a spring arranged within the hollow flange of the other member, said spring cooperating with the stud member to hold the separable members in operative relationship. 85
- 25 7. A cuff button having separable members each having a shank provided at one end with a fixed head and at the other with a radially extending flange, annular caps secured to the respective flanges, one of said caps having a convex outer surface and the other having a concave surface engaging therewith when the members are operatively positioned, a stud having a base member fixedly secured between the concave cap and its cooperating flange and a head projecting through the opening in said cap, and resilient means interposed between the other cap and flange and constituting retaining means for engagement by said stud. 90
- 30 8. A cuff button comprising separable members, each having a fixed head at one end and complementary engaging faces at their other ends, one of said faces being con- 95
- 25 9. A cuff button comprising two separable parts, each having a shank terminating at one end in a fixed head and at the other in a dished flange, said flanges being provided with cover members of convex and concave curvature respectively constructed and arranged closely to interfit with each other when the parts are operatively positioned, a wear-resistant stud having a base flange fixedly secured in the relatively shallow cavity behind the concave cover member and having a head protruding axially from the concave surface thereof, and a U-shaped spring having substantially parallel arms arranged within the relatively deep cavity behind the convex cover member, said parallel arms engaging opposite sides of the stud for holding the parts in operative relationship. 100
- 35 10. A cuff button having separable members each having a head at one end, one of said members comprising a shank having a radially extending flange, a cap secured to the flange and provided with a central opening, the material of the cap extending inwardly at the opening to form a tubular socket, and a stud projecting from the other of the members for engagement with the socket. 105
- 40 11. A cuff button having separable members each comprising a shank provided with a head at one end and having a radial flange at its opposite end, an annular cap secured to each flange, one of said caps having a tubular member extending inwardly from its central opening and constituting a socket, and a stud member projecting through the opening in the other cap for engagement with the socket, said stud member having a flange fixedly secured behind the last named cap. 110
- 45 12. A cuff button comprising separable members each having a fixed head at one end, one of said members having a headed stud at its opposite end and the other comprising a tubular socket for the reception of the stud, said socket having a slot in its wall, and spring means normally projecting inwardly through the slot and operative to engage the head of the stud to oppose withdrawal of the same from the socket. 115
- 50 13. A cuff button comprising separable members, each having a head at one end, a wear resistant headed stud fixedly secured to 120
- 55 125
- 60 130

one of said members at the end thereof opposite to the head, the other of said members having a housing provided with an axially extending tubular socket for the reception of
5 the stud, the walls of the socket having oppositely disposed slots therein, and a U-shaped spring within the housing having its

arms normally positioned within the respective slots to engage the shank portion of the stud whereby to oppose withdrawal of the 10 stud from the socket.

Signed by me at Attleboro, Massachusetts,
this 12th day of July, 1922.

EBEN F. WILDE.

Certificate of Correction.

It is hereby certified that in Letters Patent No. 1,450,344, granted April 3, 1923, upon the application of Eben F. Wilde, of Attleboro, Massachusetts, for an improvement in "Cuff Buttons," an error appears in the printed specification requiring correction as follows: Page 3, line 3, claim 3, for the word "thereof" read *and*; and that the said Letters Patent should be read with this correction therein that the same may conform to the record of the case in the Patent Office.

Signed and sealed this 1st day of May, A. D., 1923.

[SEAL.]

KARL FENNING,
Acting Commissioner of Patents.
